UNITED STATES PATENT OFFICE.

BENTON H. JACKSON, OF DAYTON, WASHINGTON.

MEANS FOR DROPPING PROJECTILES FROM AERIAL CRAFTS.

1,242,553.

Specification of Letters Patent.

Patented Oct. 9, 1917.

Application filed December 20, 1915, Serial No. 67,835. Renewed March 3, 1917. Serial No. 152,435.

To all whom it may concern:

Be it known that I, BENTON H. JACKSON, a citizen of the United States, residing at Dayton, in the county of Columbia and State of Washington, have invented certain new and useful Improvements in Means for Dropping Projectiles from Aerial Crafts, of which the following is a specification, reference being had to the accompanying drawings.

This invention relates to certain improvements in means for dropping projectiles from aerial crafts; and it is an object of the invention to provide means of this general character of a novel and improved construction whereby the projectiles are caused to drop upon an extended area.

It is also an object of the invention to provide means of this character having a novel and improved construction wherein a supply hopper or container is employed and whereby the discharge of the projectiles from said hopper may be readily and conveniently controlled.

The invention consists in the details of construction and in the combination and arrangement of the several parts of my improved means for dropping projectiles from aerial crafts whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view in side elevation illustrating an aerial craft, with an embodiment of my invention applied thereto;

Fig. 2 is a vertical sectional view taken through my improved device as herein embodied;

Fig. 3 is a view in bottom plan of the device as illustrated in Fig. 2;

Fig. 4 is a view in top plan of the deflecting member or disk; and

Fig. 5 is a sectional view taken substantially on the line 5—5 of Fig. 1.

As disclosed in the accompanying drawings, F denotes the framework of an aerial craft of any desired construction and on which is mounted the motor M operatively

engaged with the shaft S, the rotation of the shaft S under the influence of the motor M being under control of the clutch mechanism C whereby said shaft S may be caused to rotate at the convenience of an occupant of the craft.

Suitably supported by the frame F is a hopper or container 1 preferably in the form of an inverted truncated cone and having its lower or smaller end closed by the head 2 provided with a circular series of openings 3 of predetermined dimensions.

Arranged axially of the hopper or container 1 is a sleeve 4 extending below the head 2 and above the upper or open end of the hopper or container 1 and, as herein disclosed, said sleeve 4 is maintained in applied position by the braces 5 interposed between the sleeve 4 and the inner wall of the container or hopper 1 and adjacent the opposite ends of said hopper or container. The braces 5 are preferably radially disposed relative to the sleeve 4 and equidistantly spaced so as to afford a minimum of obstruction to the projectiles P initially applied within the hopper or container 1. The projectiles P may be solid shot, bombs or of any other character which is deemed expedient.

Disposed through the sleeve 4 and extending beyond the opposite ends thereof is the shaft 6 having its upper end operatively engaged, as at 7, with the shaft S whereby axial rotation may be imparted to the shaft 6 when desired. The lower extremity of the shaft 6 has affixed thereto the disk 8 arranged in a plane substantially parallel to the plane of the head 2 and said disk 8 is of a diameter in excess of the diameter of the head 2 so that the projectiles P discharged through the openings 3 will fall upon the disk 8. The disk 8 is also provided with the upstanding radially disposed flanges or webs F which serve, upon the rotation of the shaft 6, to scatter the projectiles P dropped upon the disk so that said projectiles will fall upon an extended area.

The openings 3 are of a diameter materially in excess of the diameter of the projectiles P generally employed and in order to control the discharge of the projectiles P through the openings 3, I have loosely mounted upon the lower end of the sleeve 4 the disk 9 provided with a circular series of openings 10 of a diameter substantially equal to the diameter of the openings

3 and adapted to be brought in register therewith. It will be understood that upon axially rotating the disk 9, the discharge of the projectiles P through the openings 3 5 may be readily and conveniently controlled.

As herein embodied, the marginal portion of the disk 9 overlies the brackets or guides 11 depending from the lower end of the hopper or container 1 whereby said disk 9 10 is maintained in applied position. It is also to be observed that a portion of the periphery of the disk 9 is provided with the teeth 12 with which the shaft 14 is operatively engaged, said shaft being rotatably 15 supported by the bearings 15 preferably secured to the outer face of the hopper or container 1 and extending thereabove, the upper portion of said shaft being provided with suitable means for imparting the requisite axial rotation thereto, said means being 20 herein set forth as a hand wheel of conventional type. It is to be understood, however, that I do not wish to be limited to this particular means for axially rotating the shaft 14 as other means may be employed 25 with equal facility.

The disk 9 is provided with the extension or lug 16 herein disclosed as coacting with adjacent brackets or guides 11 whereby the 30 axial rotation of the disk 9 is limited in either direction.

From the foregoing description, it is thought to be obvious that means for dropping projectiles from aerial crafts constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

50 1. Means for dropping projectiles from aerial crafts comprising a container pro-

Copies of this patent may be obtained for five cents each, by addressing the "Commissioner of Patents, Washington, D. C."

vided with a discharge opening, a rotatable disk carried by the container and provided with an opening adapted to register with the discharge opening, a peripheral portion 55 of the disk being provided with teeth, and a shaft rotatably supported by the container and operatively engaged to the teeth of the disk and provided with an operating means.

2. Means for dropping projectiles from 60 aerial crafts comprising a container provided with a discharge opening, a rotatable disk carried by the container and provided with an opening adapted to register with the discharge opening, a peripheral portion 65 of the disk being provided with teeth, and a shaft rotatably supported by the container and operatively engaged to the teeth of the disk and provided with an operating means, 70 said shaft being arranged exteriorly of the container.

3. Means for dropping projectiles from aerial crafts including a container having a discharge opening, guides carried by the 75 container, a disk rotatably supported by the container and having its marginal portions coacting with the guides, said disk being provided with an extension coacting with certain of the guides for limiting the rotation of the disk, said disk being provided 80 with an opening adapted to register with the discharge opening of the container, and means for imparting rotary movement to the disk.

4. Means for dropping projectiles from 85 an aerial craft consisting of a container provided with an annular series of openings in its bottom, a sleeve disposed axially through the container and extending below the bottom thereof, a disk rotatably engaged with 90 the lower portion of the sleeve and provided with openings adapted to register with the openings in the bottom of the container, means for imparting rotary movement to the disk, and a deflecting member 95 operatively mounted within the sleeve.

In testimony whereof I hereunto affix my signature in the presence of two witnesses.

BENTON H. JACKSON.
